AIR PULSE SWITCH HAVING INHERENT HOLDING PERIOD
 Clinton T. Cooper, 327 Melbourne Ave.,
 Youngstown, Ohio
 Filed July 25, 1963, Ser. No. 297,646
 8 Claims. (Cl. 200—83)

This invention relates generally to electrical signaling and/or indicating systems, and more particularly to an improved switch assembly for converting an air pulse generated by a detecting device into an electrical signal of predetermined character. A widely adopted use for such general apparatus is to detect and signal the ingress of a customer's automobile at a gasoline filling station, and commonly the electrical circuit established to operate an audible signal is of very short duration. Another use for such general apparatus is in the provision of means to automatically open an entrance door as a person approaches in front of it and sometimes to also trigger the closing of the door after the person has passed through it and is departing therefrom.

The air-pulse generating means employed in the above systems may comprise simply a length of flexible and collapsible hose or a collapsible mat having a dispersed air chamber therein and operative when the weight of a pedestrian's foot appears thereon to issue a pulse of air from said chamber. These air pulses, whether from a hose or a mat, are piped to impinge on a flexible diaphragm which on its other side actuates a moveable contact to establish an electrical circuit which, in turn, activates a signal, indicator, or other connected device such as a door actuator. The system must necessarily be rather sensitive and provision must be made for continuously equalizing the internal and external air pressures, it being understood that ambient temperature variations and other factors can tend to increase or decrease the air pressure within the system in relation to the air pressure on the outer side of the diaphragm. This equalization has heretofore been accomplished by providing a bleed port somewhere in the system so that pressure increases due simply to temperature changes and the like are slowly bled off to prevent unwanted closure of the switch and to permit the ingress of atmospheric air if the pressure within the system slowly falls for any reason. This method, however, makes it impossible to sustain the closure of the switch for any appreciable length of time after the detector is actuated, necessitating holding relays or other equivalent circuitry in applications where the initiating circuit must be held closed for a predetermined period of time. It is accordingly the primary object of this invention to provide an air-pulse operated switch which remains sensitive and consistent in operation through continuous equalization of air pressure within and outside the system when the pulse-generating detector is in standby condition but which is nevertheless operative for a predetermined interval after the detector is once actuated and remains actuated for a finite time period. Thus, it is possible in my invention to hold the switch closed for substantially all the time that the weight of a foot is on a mat detector or the weight of an automobile tire is on a hose tread. This makes it possible to simplify connected control apparatus and to adapt the switch to a wider variety of such apparatus.

A further object of the invention is to increase the sensitivity and consistency of operation of air-pulse operated switches while yet enabling such switches to remain closed for a substantial interval of time sufficient to insure the full actuation of connected control circuitry—for example, the completion of an actuating stroke of the movable core of a relay.

2

The above and other objects of the invention will become apparent upon consideration of the following specification and the accompanying drawing wherein there are disclosed preferred embodiments of the invention.

5 In the drawing:

FIGURE 1 is a side elevation of a pulse switch constructed in accordance with the principles of my invention;

10 FIGURE 2 is a vertical section of the switch assembly of FIGURE 1;

FIGURE 3 is a sectional view of a modified form of the invention for accomplishing the objects thereof; and

FIGURE 4 is a further embodiment of the invention.

While the operative combination of the apparatus of 15 my invention may assume many physical forms I preferably provide a hollow block 10 having a flanged annular upper opening 11 to which is attached by pressing or soldering an apertured plate 12. The lower end of the block 10 is formed in one side wall with an aperture 13 and a smaller aperture 14 is formed in the opposite side wall in alignment with the aperture 13.

20 Snugly received in the apertures 13 and 14 is an elongated shouldered fitting 15 having a thru-bore 16 therethrough which widens out at 17 and which is provided with internal threads 18 adjacent one end of the fitting. 25 As shown, the opposite end portion of the fitting has a shoulder to overlie the outer surface of the side wall adjacent the aperture 13, and this portion of the fitting has an annular groove to receive a flexible sealing O-ring 19.

30 The adjacent end extremity of the fitting is of reduced diameter, as shown.

25 Suitably supported on the side wall of block 10 concentric about the aperture 13 is a small solenoid 20 carrying a slideable armature 21 having a centrally disposed bore extending longitudinally from its inner end to slideably receive the end extremity of fitting 15 which, as pointed out above, is of reduced diameter. Interposed between the bottom wall of the bore in armature 21 and the adjacent end face of the fitting 15 is a small coil spring 22 35 which operates to bias the armature 21 to the right when the solenoid 20 is deenergized. When the armature 21 is so positioned the inner annular face of it is spaced slightly from the O-ring 19 so that communication is provided between the bore 16 and the space surrounding the armature. The latter is loosely received in the solenoid 20 so 40 that the communicating passage thus provided is, in effect, open to the atmosphere.

35 The transition between bore sections 16 and 17 is conical, as shown, to provide a valve seat, and cooperating 50 with this seat is a needle valve 23 having screw-threaded connection with the threads 18 whereby the area of communication between bore section 16 and 17 may be finely adjusted by manipulation of the member 23 outside the block 10. An aperture 24 in the side wall of bore section 55 17 provides communication between this bore section and the space within block 10. The threads 18 and cooperating threads on the needle valve 23 are sufficiently long and close fitting that little air moves along this threaded connection in either axial direction.

60 At the lower end of the block 10 is a coupling 25 by which the switch may be connected to a pulse generator such as the mat 26 shown in dotted lines in FIGURE 1. In accordance with known art, the mat 26 may be formed with a tread-like upper surface below which is disposed collapsible tubes or other means providing air spaces 65 which are interconnected and communicate with an outlet 27 for connection to the coupling 25. The device 26 operates to deliver a pulse of air through outlet 27 whenever any part of its upper tread is depressed as by a foot, for example. Soldered or otherwise suitably secured to the upper edge of the flange opening 11 of the member 70 10 is a conical disc 28 to the outer periphery of which

is cemented a sealing ring 29. Stretched across this sealing ring and suitably cemented thereto is a diaphragm 30 formed of neoprene sheet or other suitable material, and it should be understood that upon the appearance of a pulse of increased air pressure in the block 10 the center part of this diaphragm will be raised.

Suitably secured to the top face of the plate 12 is a block 31 of insulation material which carries, first, a flexible conductive strip 32 mounting an electrical contact point on the upper surface of its free end and a pad therebelow for overlying the center portion of the diaphragm 30, a second flexible conductive strip 33 is also carried by the block 31 and mounts on the lower surface of its inner free end the second switch contact. The vertical position of the inner free end of strip 33 and consequently the switch contact carried thereby is arranged to be adjusted by a screw 34 which passes down through a threaded aperture in the upper wall of a cover 35 which is affixed to the plate 12 to enclose the switch assembly.

In actual practice, suitable insulated conductors 36 are connected to the conductive strips 32 and 33 and lead out of the casing formed of the parts 12 and 35 to the control apparatus with which the pulse switch is associated. The solenoid 26 is connected in series with one of the conductors 36 so that the solenoid will be energized simultaneously with the closing of the switch contacts, it being assumed, of course, that in accordance with usual practice the control apparatus will have suitable circuitry to energize the conductors 36 when the switch is closed.

In the operation of the apparatus described above, it will be apparent that during standby the valve formed by ring 19 will be open allowing equalizing air to enter and exit from the block 10 at a rate determined by the setting of the needle valve 23. Thus, the air pressure on both sides of the diaphragm 30 remains equalized and any compression in the system as caused by the pulse generator will immediately tend to flex the diaphragm 30 and close the switch. However, the sensitivity may be readily adjusted by adjusting the needle valve 23 because when this needle valve is open minor pulsations can still be bled off through aperture 24 and bores 17 and 16 before the diaphragm flexes sufficiently to close the switch. This sensitivity adjustment may be used, for example, to prevent pelting rain to trigger off a door opening system. When, however, the detector or mat 26 is sufficiently actuated to generate a compression pulse which cannot be dissipated rapidly by the bleed port the switch will be closed and simultaneously the solenoid 26 will be energized to close off the bleed port and hold the switch closed so long as the detector remains compressed, even if only in part. The practical effect of this is to keep the switch closed for an appreciable or finite length of time sufficient to actuate the associated control apparatus. Heretofore, pulse switches of the kind herein considered have been erratic in operation because the bleed or equalizing port remained open and if the diaphragm did flex sufficiently to close the contacts they often remain closed only momentarily and too short a time for full actuation of the associated control.

In the embodiment of the invention shown in FIGURE 3 there is utilized a conventional diaphragm-operated switch designated generally by reference numeral 40. Leading to this assembly and providing communication with the inner side of the diaphragm thereof is a conduit 41 which is connected first to an air-pulse generator 42 which may be similar in all respects to the generator 26 described briefly above. Also connected to the conduit 41 is a block 43 mounting a flexible diaphragm 44 the inner side of which communicates with the conduit 41 through a passageway 45 formed in the block 43. Overlying the outer peripheral edge portion of the diaphragm 44 but slightly spaced therefrom is an apertured cover member 46 mounted on the block 43. A needle valve 47 and a cooperating passageway 48 provides an adjust-

able bleed port between the passageway 45 and the space within the cap 46.

The bleed port provided by needle valve 47 normally permits the ingress and egress of air into the system including the mat or generator 42 and the switch assembly 40 to compensate for changes in ambient temperature as explained above in connection with the embodiment of FIGURES 1 and 2. It should be noted, however, that the parts 44 and 46 are so related that as the diaphragm 44 expands outwardly by the application of a pulse of air to the passage 45 the space within the cap 46 is sealed off by reason of the diaphragm engaging the edges of the aperture in cap 46. Therefore, so long as the mat or generator 42 remains depressed by a footstep, for example, the increased pressure built up in conduit 41 will remain fixed to hold the switch 40 closed.

It should be understood that the showing in FIGURE 3 is illustrative only since the illustrated means for closing off the bleed port can as well be built into the generator 42 or in the switch assembly 40 wherein the switch-actuating diaphragm itself would also constitute the automatic valve for closing off the bleed port.

In the embodiment of the invention shown in FIGURE 4 the general arrangement is similar to that shown in FIGURE 2 except that the solenoid 49 for closing the bleed port valve is housed in a recess formed in a block 50 which also forms the general support of the switch. Block 50 is provided with a passage 51 adapted to be connected to the pulse generator, and it should be noted that this passage leads to the switch-actuating diaphragm (52) and provides an inlet for the bleed port, the latter being adjusted by the needle valve 53 and being adapted to be closed by the valving ring mounted on the inner end of the solenoid plunger 54. The structure of FIGURE 4 thus far described operates in the same manner as does the apparatus of FIGURE 2 in that by means of suitable circuit connections, not shown, the solenoid 49 is energized simultaneously with the closing of the switch contacts to block the bleed port.

In FIGURE 4, however, I provide an additional feature to boost the quantity and pressure of the air in the system upon closing of the switch contacts thus reinforcing the closing force of the diaphragm on the electrical contacts and replacing whatever air escapes through the needle valve in the interval between the closing of the electrical contacts and blocking of the bleed port. All this is accomplished by mounting a disk 55 on the plunger 54 to bear against an annular collapsible air container 56 which is in communication with the passage 51 through a connecting passage 57. Now when the solenoid 49 is energized upon closing of the switch contacts and the plunger 54 is drawn downwardly a quantity of air in the container 56 will be discharged outwardly into the passage 51 to provide the pulse reinforcement explained above.

It should now be apparent that I have provided improved air-pulse operated switching arrangements which accomplish the objects initially set out in that while they provide for continuous standby pressure equalization on opposite sides of the actuating diaphragm and thus for a wider range of sensitivity in operation they nevertheless are capable of holding the contacts closed for an adequate length of time if contact is once established.

It should be obvious from the above that the principles of the invention may be embodied in various physical designs. Reference should therefore be had to the appended claims in determining the spirit and scope of the invention.

Having thus described my invention what I claim is:

1. In combination, a pneumatically operated switch, an air-pulse generator, means establishing communication between said switch and generator comprising a passage, a bleed port in a wall of said passage whereby the standby air pressure in said passage is continuously equalized with the atmospheric air pressure, and means to auto-

matically close said port simultaneously with the closing of said switch.

2. Apparatus according to claim 1 further including means manually engageable from outside said passage to control the effective area of said port.

3. Apparatus according to claim 1 further characterized in that said means to close said port comprises a normally open solenoid-operated valve, and circuit means to energize said solenoid upon closing of the switch contact.

4. Apparatus according to claim 1 further characterized in that said switch comprises a movable contact, a diaphragm for moving said movable contact, a normally fixed contact adapted to be engaged by said movable contact, and means to finely adjust the position of said normally fixed contact toward and away from said movable contact.

5. Apparatus according to claim 2 further characterized in that said switch comprises a movable contact, a diaphragm for moving said movable contact, a normally fixed contact adapted to be engaged by said movable contact, and means to finely adjust the position of said normally fixed contact toward and away from said movable contact.

6. In a pneumatically operated switch, a hollow body member adapted to be connected to an air-pulse generator and being closed in part by a flexible diaphragm, a normally fixed contact member and a cooperating movable contact member having driving connection with and actuated by said diaphragm and both contact members being positioned outside said body member, an elongated tubular fitting extending through opposite walls of said body member in air-tight relation therewith, said tubular member being of increased internal diameter in its portion extending through one of said opposed walls, and having internal screw threads in said portion, a needle valve screw-threadedly received in said portion having its pointed inner end received within the inner end of the smaller internal diametered portion of said fitting, an aperture in the side wall of said fitting to provide a passage between the space within said body member and the enlarged portion of the opening through said fitting, means outside said body member to effectively close off the outer end of the smaller internal diametered portion of said fitting, said means to close off comprising an axially outward facing sealing ring carried by said fitting, a solenoid carried by said body member concentrically about said fitting, an armature slideably received within said solenoid and having a centrally disposed bore in its inner end portion to provide an annular valving land for engagement with said sealing ring, and yieldably means normally biasing said armature to outer position whereby said valving land is out of contact with said sealing ring, and a circuit interconnecting said switch contacts

and said solenoid in series to energize the solenoid upon closure of the switch contacts to move said armature and said annular valving land into pressure engagement with said sealing ring.

5 7. A pneumatically-operated switch assembly comprising a horizontally disposed plate and an inverted cup-shaped closure over said plate to provide a switch housing, a closure block mounted on said plate and carrying a superimposed spaced pair of flexible conductive strips carrying 10 opposed switch contacts at their outer free ends, means extending through said closure to adjust the position of the free end of the uppermost of said strips, a hollow body member open at its upper end carried by said plate in depending relation thereto and mounting at its 15 upper open end a flexible diaphragm which is positioned within said housing, the free end of the lowermost of said strips overlying said diaphragm whereby upon lucture of said diaphragm in an upward direction the switch contacts will be considered to be mutually engaged, means to connect said hollow body member to an air-pulse generator, means carried by said body member to establish an 20 adjustable bleed port in a wall of said body member, and means to close off said port simultaneously with the closing of said switch contacts.

25 8. In a pneumatically-operated switch assembly, a hollow body member providing a space closed off in part by a switch actuating diaphragm and adapted to be connected to an air-pulse generator, a tubular fitting extending through opposite side walls of said member and having a flange adjacent one end thereof to overlie the outer surface of one of said side walls, said flange having an annular groove to mount a sealing ring which is exposed in an axial outward direction, a screw-threaded needle valve extending into said fitting from the other end thereof and an aperture in said fitting whereby a controlled 30 bleed port may be established between said space and the said one of said fitting, a solenoid carried by said one side wall concentrically about said fitting, an armature slideably received in said solenoid and having a bore extending axially from the inner end thereof for slideably mounting over the adjacent end of said fitting outwardly of said sealing ring, means in the bottom of said bore to bias said armature in an outward direction, and the annular inner end face of said armature being adapted, 35 upon energization of said solenoid, to be moved into pressure-sealing relation with said ring.
